DESIGN FOR A GYM-SHOE

William H. Allgaier, Jamaica, N. Y.

Application September 24, 1942, Serial No. 108,326

Term of patent 3½ years

To all whom it may concern:

Be it known that I, William H. Allgaier, a citizen of the Republic of Switzerland, residing at Jamaica, in the county of Queens, State of New York, have invented a new, original, and ornamental Design for Gym-Shoe, of which the following is a specification, reference being had to the accompanying drawing, forming part thereof.

In the drawing:

Fig. 1 is a top plan view of a gym-shoe showing my new design.

Fig. 2 is a side elevation thereof.

Fig. 3 is a front end view.

My design for a gym-shoe having a depressed toe-portion is characterized by the configuration and arrangement of the various parts constituting the same.

I claim:

The ornamental design for a gym-shoe, as shown and described.

WILLIAM H. ALLGAIER.
